(57) **CLAIM**

The ornamental design for a “broom,” as shown and described.

DESCRIPTION

FIG. 1 is a perspective view showing a “broom” incorporating the design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The sections of the handle shown broken away in FIGS. 1-5 indicate that they are of an indeterminate length.
